UNITED STATES PATENT OFFICE.

THEODORE ABBOTT, OF PHILADELPHIA, PENNSYLVANIA, ASSIGNOR TO
JOHN C. GRAHAM, OF SAME PLACE.

DESIGN FOR FRINGE.

SPECIFICATION forming part of Design No. 13,070, dated July 25, 1882.

Application filed June 19, 1882. Term of patent 14 years.

To all whom it may concern:

Be it known that I, THEODORE ABBOTT, of the city and county of Philadelphia, in the State of Pennsylvania, have invented and produced a new and original Design for Fringe, of which design the following is a specification.

The accompanying drawing is a side view of a section of fringe embodying and illustrating my design, which consists in a fringe composed of a series of chenille pendants, A, connected to and depending from a "moss" heading, B—that is to say, a heading formed of a

strip or web of fabric having a close series of threads or fibers projecting from its surface in the manner of a natural growth of moss, and presenting the appearance or effect thereof.

I claim—

A design for fringe, consisting of a series of chenille pendants united to and depending from a moss heading, substantially as set forth. 20

THEODORE ABBOTT.
